WILLIAM M. ISAACS, OF CLEVELAND, OHIO.

COMBINED COLLAR BUTTON AND BUTTONER.

1,275,931.

Specification of Letters Patent. Patented Aug. 13, 1918.

Application filed June 30, 1916. Serial No. 106,746.

To all whom it may concern:

Be it known that I, WILLIAM M. ISAACS, a citizen of the United States, residing at Cleveland, in the county of Cuyahoga and State of Ohio, have invented a certain new and useful Improvement in Combined Collar Buttons and Buttoners, of which the following is a full, clear, and exact description, reference being had to the accompanying drawings.

This invention relates to a novel device having the double purpose of a collar button and buttoner, it being the general object of the invention to provide a device of this nature, which, while constituting a particularly desirable collar button—possessing neatness and efficiency, and assuring comfort to the wearer—serves also as a collar buttoner—taking the place of prevailing forms of collar buttoners, which are more or less inconvenient of use and injurious to the button holes—the device being so constructed that the collar may be very easily disconnected therefrom.

Stated in more specific terms, the invention may be said to have as its main object the production of a device comprising a base, a neck which projects therefrom, and a combined head and buttoning member extending laterally from the neck, and which may be readily placed in the button holes of the collar band and, by inserting the entering end of the buttoning member into first the button hole at one end of the collar and turning it in an appropriate direction, will cause said end of the collar to travel therewith along to wearing position where the button hole automatically slips over and embraces the neck of the button, and then by inserting said member into the button hole at the other end of the collar and reversing the operation, will draw the second end of the collar to wearing position, after which the buttoning member may be turned to lie alongside the last mentioned end of the collar and hold it snugly against the collar band.

Further objects are to so design and construct the device that its operation may be performed naturally and instinctively and therefore as readily by a novice as by one who is accustomed to using it; to make the buttoning member, which constitutes, in part, the head of the button, slender and gradually tapered toward its entering end

so that it will readily pierce and gently spread the button hole and move freely therein without the slightest injury to the button hole, and to make such part of sufficient length to allow it to reach out and meet the collar without having to pull the collar toward wearing position; to design the portion of the head remote from the entering end of the buttoning member in such manner as to cause it to automatically eject through the button hole as soon as the latter is brought into register with it; to so form the last mentioned portion that it will answer, in some cases, as a holding device for the tie; and to design the device, generally, so as to insure comfort to the wearer, and so that it may be entirely concealed beneath the tie when in use.

While the device is of general utility, the fact of its possessing the features above enumerated makes it especially suitable for use with full dress shirts and collars, for apparel of this class is usually starched stiff and the collars, as a general rule, fit the collar bands more snugly than those used in ordinary wear. It is customary, therefore, in donning full dress collars, to use a collar buttoner. In the use of an instrument of this kind, an undue strain is placed upon the button holes while turning the comparatively wide loop of the buttoner within the holes, during the operation of drawing the collar to wearing position, with the result that the button holes are drawn out of shape, and in many cases, actually torn; and after the button holes have been pulled to buttoning position, it is then necessary to force the button holes over the head of the button, and this is often the source of considerable annoyance and further injury to the button holes. By means of the device which I have invented, the foregoing operation may be very conveniently performed and relieved of the difficulties above mentioned, to wit, undue strain upon or spreading of the button holes—absolutely the only force applied to the collar being that required to draw it to its final position. The liability of soiling the collar through vigorous handling is thus eliminated. Furthermore, when the buttoning operation has been performed, the button is, as a consequence thereof, within the button hole, and need only be turned thereafter to its normal position where it lies closely

along the collar and serves to hold the collar snugly against the collar band and, as above mentioned, may serve, in some instances, to hold the tie in position. Also, my device does away with the handling of two separate articles and avoids misplacement of the buttoner.

While the buttoning operation is usually the most difficult in the matter of dealing with stiff collars, the unbuttoning of the collar is not to be disregarded. It is often quite difficult to remove the button hole from the head of a collar button of usual size. In my device, this is rendered extremely easy by the fact that only a short nib extends in the direction of the end of the collar, and is of substantially the same or less width than the neck of the button. Consequently the end of the collar may be readily lifted over such nib to free it therefrom. Therefore, I consider the fact of the head being no greater in width than the neck of the button, of marked importance.

In the accompanying drawing I have illustrated two constructions of my combined collar button and buttoner wherein the foregoing objects are attained, and which possess the advantages above set forth; and while I will proceed to describe these embodiments of my invention in detail, I wish to be understood as not confining myself to the structural details thereof further than is required by the terms of the annexed claims.

In the drawing, Figure 1 is a perspective view of the device of my invention; Figs. 2, 3, 4 and 5 are diagrams illustrating the various steps in the operation of buttoning a collar by means of the device; Fig. 6 is a horizontal section through the collar band, collar, and tie, which are held in correct relative position by the device; and Fig. 7 is a sectional detail of a modification.

The device comprises a base 1 from which a neck 2 projects centrally, and a combined head and buttoning member 3 extends laterally from the outer end of the neck. This member is preferably inclined and curved gradually toward the plane of the base 1, and its outer end is somewhat pointed to facilitate its entering a button hole. A short nib 4 extends in the opposite direction from the outer end of the neck 2, and is spaced a slightly greater distance than the member 3 from the base 1 for a purpose which will become apparent when the operation of the device is explained. For a further purpose, the underneath surface of the nib 4 is made quite abrupt to the adjacent surface of the neck 2, thus constituting a sort of hook, and it is somewhat in advance of the plane of the inner side of the member 3, as will be best seen from Figs. 6 and 7.

While the button may be made according to any suitable method common to button manufacture, with the parts relatively fixed,

I suggest, as a modification of the invention, the construction illustrated in Fig. 7 wherein the neck is swiveled to the base, thus permitting the head and button member, together with the neck, to freely rotate with respect to the base, during the buttoning operation. In this form of my invention, the inner end of the neck 2 is reduced at 5 and passes through a central aperture in the washer 6, the reduced end of the neck being then upset to form a flat head 7. This produces a swivel connection between the neck 2 and the washer, and the washer, with the head 7, may then be backed by a cap or plate 8, having its periphery turned forward and inward over the edge of the washer 6, as shown at 9. The operation of both forms are identical, and will now be explained.

The button is first placed in the button holes of the collar band, and this may be accomplished in the manner which I will now describe in buttoning the collar, although the buttoning member has not ordinarily so much purpose in buttoning the collar band as in buttoning the collar, for the reason that there is considerable "go and come" to the collar band, because of its comparative softness and the pliability of the neck. Now in buttoning the collar, the button hole at one end of the collar is placed over the end of the buttoning member, as illustrated in Fig. 2. By grasping the protruding end of the member, it may be swung in the direction indicated by the arrow until the nib 3 is in register with the button hole. By reason of the fact that the nib is somewhat higher than the plane of the inner end of the buttoning member, the collar is placed under a bending tension in the region of the button hole, so that as soon as the nib is in a position to pass through the button hole, the button hole automatically snaps down over the nib and assumes its position on the neck 2. Through this step in the operation, the buttoner is placed in position to receive the opposite end of the collar, in which condition it is illustrated in Fig. 3. Now, by swinging the collar button in the reverse direction, as indicated by the arrow in Fig. 3, the foregoing operation is repeated in connection with the opposite end of the collar, and the parts are then found in the condition illustrated in Fig. 4. The button is then returned in the direction indicated by the arrow in the last mentioned figure, to the position illustrated in Fig. 5, where the buttoning member bears against the side of the collar, and forces it snugly against the collar band, as better illustrated in Fig. 6.

At this point in the description of the operation of the device it will be well to call attention to the ease with which the collar may be unbuttoned, such operation requiring only a slight drawing of the outer

tab of the collar toward the end of the nib 3, when it may be swung outward there-over.

In Fig. 6 I have shown a common form 5 of "dress" tie, held in position by the collar button. This form of tie is made like the ordinary string tie, except it is provided with a central hole which buttons over the back collar button, and spaced at equal distances in both directions from the central 10 button hole, are tabs having button holes for application to the front button. Beyond these tabs there is sufficient material to produce the bow.

15 In the illustration, one tab of the tie 14 is shown at 15 as embracing the neck of the button, adjacent the outer layer of the collar, and the opposite tab 16 is shown as overlying the buttoning member and hooked 20 over the nib 4.

Having thus described my invention, what I claim is:—

1. As a new article of manufacture, a collar button comprising a base, a neck projecting therefrom, and a combined head and buttoning member permanently carried by the neck and extending laterally therefrom toward the plane of the base and beyond the edge thereof, as and for the purpose 30 specified.

2. As a new article of manufacture, a collar button comprising a base, a neck projecting therefrom, a combined head and buttoning member extending laterally in one 35 direction from the neck, and a nib extending from the neck in the opposite direction, said nib being spaced farther than said member from the base.

3. As a new article of manufacture, a collar button comprising a base, a neck projecting therefrom, a combined head and but- 40

toning member extending laterally in one direction from the neck, and a nib extending from the neck in the opposite direction, the outer surface of the nib being in advance of the corresponding surface of the aforesaid member. 45

4. As a new article of manufacture, a collar button comprising a base, a neck projecting therefrom, a combined head and buttoning member extending laterally in one direction from the neck, and a nib extending from the neck in the opposite direction, the inner surface of the nib being spaced farther than the corresponding surface of 55 said member from the base.

5. As a new article of manufacture, a collar button comprising a combined head and buttoning member, a neck from one end of which said member extends laterally, the 60 opposite end of the neck being reduced to provide a shoulder, a washer through which the reduced portion of the neck freely passes, said portion being upset therebeyond to form a head, and a cap which conceals 65 said head and has its periphery turned forwardly and inwardly about the edge of the washer.

6. As a new article of manufacture, a collar button comprising a combined head and buttoning member, a neck from one end of which said member extends laterally, a washer through which the opposite end of said member freely passes and is upset to 70 form a head therebyond, and a cap for con- 75 sealing said head and having its periphery bent forward and inward about the edge of the washer.

In testimony whereof, I hereunto affix my signature.

WILLIAM M. ISAACS.
